UNDERCLEARER MOUNTING IN TEXTILE SPINNING, PREPARING, AND LIKE MACHINES

William Wilson, Accrington, England, assignor to Howard and Bullough, Limited, Accrington, Lancashire, England, a British company

Application May 14, 1938, Serial No. 208,034
In Great Britain May 18, 1937

1 Claim. (Cl. 19—140)

The invention has reference to the mounting of the underclearer rolls in the drafting apparatus of textile spinning, preparing or speed frames and like machines, and its principal object is to provide an improved form of such mounting whereby the underclearers may be rendered accessible for stripping as completely and as expeditiously as possible. A further object is to provide mounting means which will be of the simplest possible form of construction and embodying a minimum number of component parts, in order to minimize the initial cost of manufacture and so that the time required for cleaning the same may be as short as possible.

An underclearer mounting in accordance with the said invention comprises a pivotally mounted rocking lever adapted to support the underclearer roll at its free end where it is also provided with a finger-piece or handle for movement out of the operative position to a position in which the roll is easily accessible for stripping.

The invention is further characterised by pivoting the rocking lever about a centre so disposed relatively to the operative position of the underclearer and the centre of the associated draft roller that, when moved from the operative position, the rocking lever must pass over a dead centre, and the seating of the underclearer roll is adapted to yield sufficiently to permit of such movement at the times desired.

Adjustable stops, abutments or the like, may be provided for regulation of the precise settings of the underclearer in the operative and "stripping" positions.

The nature of the invention is hereinafter more fully described with reference to the accompanying drawings, in which Fig. 1 is a side view of the drafting apparatus of a ring spinning frame, having the mounting of the underclearer of the back roller constructed in accordance with the present invention. Fig. 2 is more or less a diagrammatic view of the relevant portion of the apparatus illustrated in Fig. 1, showing the underclearer mounting in the retracted or "stripping" position. Fig. 3 is an elevation of the underclearer mounting shown separately, and Fig. 4 is a detail view in perspective of the cushioning spring employed in the underclearer bearing.

In the drawings, 5 represents the back or feed roller of the drafting range and 6 a single tape employed in the intermediate stage between said roller 5 and the front roller 7, said tape 6 being guided over a tensioning roller 8 which is supported by a bracket 9 pivotally suspended from a fixed shaft running longitudinally along the rear

of the rollerstand. The shaft 10 is also utilised to support a bracket 11 off-set forwardly therefrom, and upon a pivotal stud 12 fixed in said bracket is mounted a rocking lever 13 of which the free extremity is provided with an open bearing 131 forming a seating for the shaft-journal 141 of the underclearer 14. It will be understood that each underclearer 14 is supported at its centre by a rocking lever 13 which is carried by a fixed bracket 11 and all such brackets 11 are mounted upon the common shaft 10.

Each rocking lever 13 is provided with an integral tail-piece 132 adapted to impinge against the shaft 10 in such manner as to limit the forward movement of the rocking lever about its pivot 12. In addition, an adjustable stop, formed by a locked setscrew 132a passing through the tail-piece 132, may be provided for each rocking lever 13, for use in the circumstances hereinafter referred to.

In the operative position of the rocking lever, i. e. as illustrated in Fig. 1, the underclearer roll 14 presses against the back roller 5 and rotates in contact therewith, the pressure between the underclearer 14 and the roller 5 being sufficient to maintain the former in its bearings. A finger-piece is provided at the free end of each rocking lever 13, consisting of an integrally formed offset projection 15 extending rearwardly to a point in which it is easily accessible from the rear of the roller-stand, and the arrangement is such that by pressing downwardly on said finger-piece 15 the lever 13 may be pivoted about its pivot 12 into a position in which the underclearer roll 14 is readily available for stripping or removal. In this position, illustrated in Fig. 2, the rocking lever 13 rests against the aforesaid horizontal shaft 10.

The arc of travel of the underclearer roll 14 between the operative and "stripping" positions is arranged to intersect the line joining the centres of the pivot 12 and the back roller 5, so that the rocking lever 13 must pass over a dead centre when moving from the operative position into the "stripping" position, and in order that the underclearer roll 14 may yield downwardly to a sufficient extent to enable it to pass beneath the periphery of the roller 5, the seating of the bearing 131 is furnished with a spring 16 upon which the shaft journal 141 of the underclearer may rest, said spring being arranged normally to urge the underclearer 14 against the roller 5. By these means I ensure that the lever 13 will not be inadvertently displaced from the operative position during working by the rotary action of the

roller 5 on the underclearer roll 14. The spring 16 may be provided with projecting tongues 161, as shown in Fig. 4, which are adapted to register with and enter slots or recesses in the sides of the lever 13, thus retaining the spring 16 in position.

In the particular form of drafting apparatus illustrated in the accompanying drawings, the underclearer mounting can be so arranged as to allow the underclearer roll 14 to rest lightly 10 against the face of the belt or tape 6 to clear waste fibres therefrom, and the pressure with which the underclearer 14 is allowed to bear against said belt or tape may be varied by regulating the adjustable stop hereinbefore referred 15 to as being provided in the tail-piece 132 of the lever 13, so as to vary the scope of pivotal movement of the rocking lever 13 to the required extent.

In another embodiment of the invention, not 20 shown, the form of mounting herein described is

applied to an underclearer working in conjunction with a front drafting roller; in such case, the rocking lever may be arranged to pivot forwardly out of the operative position to a point at which it is readily available to the operative 5 standing in front of the roller stand.

What I claim as my invention and desire to secure by Letters Patent is:

In a textile machine, a drafting roller, an underclearer roll, a shaft extending longitudinally 10 throughout the machine, a bracket offset from said shaft, a rocking lever pivotally mounted on said bracket and supporting the underclearer roll at its free end, a finger-piece on said bracket for swinging the latter to a position in which the roll is easily available for stripping, and a tail-piece 15 on said lever engageable with said shaft for limiting the movement of the lever.

WILLIAM WILSON.
